UNITED STATES PATENT OFFICE.

AUGUSTE DACCORD, OF NEW YORK, N. Y.

BOTTLE-CLOSURE.

1,327,809.

Specification of Letters Patent. Patented Jan. 13, 1920.

Application filed March 28, 1918. Serial No. 225,227.

To all whom it may concern:

Be it known that I, AUGUSTE DACCORD, a citizen of the Republic of Switzerland, and a resident of the city of New York, in the county and State of New York, have invented a certain new and useful Improvement in Bottle-Closures, of which the following is a specification, reference being had therein to the accompanying drawing.

10 This invention relates to stoppers for bottles, and more particularly to devices of the kind which are used in connection with wide-mouthed bottles designed to hold milk and cream.

15 Numerous contrivances have heretofore been devised for the purpose of providing a suitable closure for the orifice of a milk-bottle, but in so far as I am aware none that has proved to be entirely satisfactory, considered both with reference to ease of manipulation and from an economic standpoint. Perhaps the least expensive and most employed form of stopper of this type formerly in use was that which consisted of 20 a flat disk of paper, and was rammed tightly into the mouth of the milk-bottle, wherein it rested at the edge upon an internal flange formed in the bottle-neck. A stopper of that sort answered the purpose to the extent 25 that it closed the bottle until first opened after delivery, but it was subject to the positive disadvantage of requiring the use of a tool or some sharp instrument for its removal. This most always resulted in puncturing or cutting up the paper disk, and consequently the same could not thereafter be replaced in the mouth of the bottle, if so desired, and serve again as a dust-proof closure.

30 The principal object of the present invention is to provide an improved closure of the type aforesaid which shall not only afford adequate protection to the contents of the bottle, but can be easily removed therefrom 35 without the use of a tool or other implement of any description, and may also be set back in place as often as required to keep the bottle properly closed, when only partially emptied.

40 Other objects and advantages of the invention will become apparent as the specification proceeds.

Referring to the drawing hereto annexed, for a detailed description of the invention,

55 Figure 1 is a sectional elevation, showing

the neck or upper part of a milk-bottle, with this improved closure thereto applied;

Fig. 2 is a similar view, illustrating the manner of removing the closure from the 60 mouth of the milk-bottle;

Fig. 3 is a perspective view of the closure, detached, looking at the top thereof; and

Fig. 4 is another perspective view of the closure, looking at the under side of the 65 same.

As represented in Figs. 1 and 2, the invention is readily applied to a milk-bottle, indicated by the numeral 11, such as is employed by dairymen or distributors of dairy 70 products. This form of bottle, it will be noted, has a wide neck 12, with a proportionately large mouth 13, and an internal ledge 14, constituting an annular abutment at the division line between the mouth and 75 neck. Ordinarily, the bottle is filled up to within a small fraction of an inch of the ledge or abutment.

Taking the bottle above described, the improved closure adapted therefor consists 80 of a slightly conical disk 17, of convexo-concave formation, adapted to be seated at its perimeter upon the ledge or abutment 14 aforesaid. This disk is conveniently made of smooth cardboard, calendered, and 85 stamped in one piece with suitable dies, of the form and dimensions required to suit the various requirements. It is given sufficient flexibility to permit inversion, that is, to be readily changed, by pressure thereon, from the convexo-concave to the concavo-convex shape, and the reverse, at option. At the same time, enough rigidity is imparted to the disk to render it capable of retaining the desired form in normal conditions. It is further made somewhat larger than the internal area of the mouth of the bottle, that it may press lightly all around the same at the outer circumference of the ledge or abutment.

100 It will be observed that when set in place within the mouth of the bottle, as illustrated in Fig. 1, the disk 17 stands therein with its apex a little below the top of the bottle, so that if the latter were turned upside down, accidentally or otherwise, no part of the disk would come into contact with an ordinary plane surface or any point of a common support. Further, it will be noted that there intervenes a vacant space, indicated by the reference numeral 18, between the under side of the disk and the surface

of the liquid, as milk or cream, in the bottle, which provides all the requisite clearance for the inversion of the cone of which the closure is formed.

- 5 Now, it will be perceived that, in order to remove the closure, the only thing needed is to press down, for instance with the thumb, upon the apex of the conical disk 17, when the same will become inverted and
 10 thereby unseated from the abutment 14, upon which it previously rested. The small quantity of air confined in the space 18 causes the edge of the disk to be disengaged from the surrounding wall in the mouth of the
 15 bottle, owing to compression resulting from the inversion of the cone, and then a slight push with the thumb will eject the disk, after the manner suggested in Fig. 2. In case the bottle is not emptied at once of all its contents, it is a simple matter to restore the disk to its original shape, or else to reverse
 20 it, and put it back in the mouth of the bottle, which can thus be opened and closed repeatedly, without the use of any tool.
 25 Although the invention has been shown and described as a closure especially adapted for use on a milk-bottle, it should be understood that no undue limitation of the inven-

tion is intended in that respect. Obviously, this improved closure could be used on jars 30 and various types of containers other than bottles for holding milk or cream. The contents of the jars, bottles, or similar vessels, of course, have little if any bearing on the invention, in so far as the construction and 35 operation of the closure are concerned.

Having described my invention, what I claim, and desire to secure by Letters Patent of the United States, is:

The combination with a bottle or similar 40 vessel having a relatively wide neck, a proportionately large mouth, and an internal abutment therebetween, of a slightly conical convexo-concave disk adapted to be seated at its outer edge upon said abutment 45 and form a tight closure thereon with its apex below the top of the bottle or vessel, said disk admitting of inversion by pressure upon its said apex, being thereby disengaged from its seat on the abutment and 50 positioned for ejection from the bottle or vessel by a thrust in a substantially lateral direction.

In testimony whereof I have signed my name to this specification.

AUGUSTE DACCORD. [L. S.]
